LLP; Paul D. Bangor, Jr.

(21) Appl. No.: **29/339,380**

(57) **CLAIM**

(22) Filed: **Jun. 29, 2009**

The ornamental design for a railroad tie hybrid extender/conductor rail support insulator, as shown and described.

(51) **LOC (9) Cl.** 12-03
(52) **U.S. Cl.** D12/51
(58) **Field of Classification Search** D12/42,

FIG. 1 is a perspective top view of a railroad tie hybrid extender/conductor rail support insulator of the present invention.

FIG. 2 a left side elevation view of the railroad tie hybrid extender/conductor rail support insulator of FIG. 1.

FIG. 3 is a right side elevation view of the railroad tie hybrid extender/conductor rail support insulator of FIG. 1.

FIG. 4 is a top plan view of the railroad tie hybrid extender/conductor rail support insulator of FIG. 1.

FIG. 5 is a bottom plan view of the railroad tie hybrid extender/conductor rail support insulator of FIG. 1.

FIG. 6 is a front view of the railroad tie hybrid extender/conductor rail support insulator of FIG. 1; and,

FIG. 7 is a rear view of the railroad tie hybrid extender/conductor rail support insulator of FIG. 1.

In the drawings, the broken lines shown in the Figures depict unclaimed subject matter only and form no part of the claimed design.
